UNITED STATES PATENT OFFICE.

WILLIAM V. ANDREWS, OF NASHVILLE, TENNESSEE, ASSIGNOR OF ONE-HALF TO
WILLIAM S. HARRIS, OF NASHVILLE, TENNESSEE.

RETAINER FOR DISINFECTANTS.

1,170,387.

Specification of Letters Patent.

Patented Feb. 1, 1916.

Application filed June 2, 1915. Serial No. 31,745.

To all whom it may concern:

Be it known that I, WILLIAM V. ANDREWS, a citizen of the United States, residing at Nashville, in county of Davidson 5 and State of Tennessee, have invented certain new and useful Improvements in Retainers for Disinfectants, of which the following is a specification.

My invention relates to an improvement 10 in retainers for disinfectants adapted to be used in flush-tanks, the object being to provide a simple arrangement to be located within the tank where it holds a disinfectant, and which is discharged into the surrounding tank by the water from the re-fill pipe.

The invention consists in a retainer, in which either solid or liquid disinfectant is placed, this retainer having a transverse 20 diaphragm some distance below the top, upon which a supply from the interior of the retainer is held between the flushing of the bowl, at which time it is discharged and a fresh supply is caught above the dia- 25 phragm or partition.

In the accompanying drawings, Figure 1 is a vertical longitudinal sectional view. Fig. 2 is a sectional elevation of the disinfectant retainer, and Fig. 3 is a top plan 30 view thereof.

A, represents the flush-tank, and the numeral 1 is the retainer for disinfectant. This is supported upon the usual overflow tube 2 (used in all modern flush-tanks) 35 conveniently by the spring-clip 3, the two jaws of which embrace the tube from opposite sides, and by the overflow spout 4 and overflow pipe 5 leading from the two compartments respectively of the retainer 1.

40 The retainer is divided into upper and lower chambers C and D by the horizontally-disposed partition or diaphragm 6. A threaded opening 7 is formed in this diaphragm through which the disinfectant, 45 either solid or liquid, is poured. This threaded opening is closed by the screw-cap 8, and the latter has an inlet 9, through which the disinfectant rises into the upper compartment with the flushing of the tank 50 after the lower compartment of the retainer shall have been filled.

The numeral 10 represents the re-fill tube rising from the ball-cock 11, and which re-fill tube discharges into the retainer at some

point below the horizontal partition or dia- 55 phragm 6.

The screw-cap has a cross-bar 12 which retards the flow of liquid which rises through the inlet 9. This cross-bar also serves as a handle by which to turn the screw-cap.

As shown in the drawing, the usual ball-valve 14 and float 15 are employed.

When the tank has been flushed, water passes through the refill tube in the usual 65 manner into the disinfectant receptacle 1, becomes thoroughly impregnated with the disinfectant, the greater portion of which passes out through the pipe 5 into the overflow tube 2, while at the same time a portion 70 of this disinfectant fluid passes through the inlet or opening 9 into the screw-cap 8, and thence into the open receptacle C at the top, where it remains disinfecting the flush-tank with its fumes until the tank is again 75 flushed, when it is forced out through spout 4 into the overflow tube 2, whereupon the compartments C and D of the retainer are again filled from the re-fill, as previously explained. 80

I claim:

1. A detachable retainer for disinfectant divided into two compartments, each of which has an independent outlet into the overflow tube of the flush-tank. 85

2. The combination with a flushing-tank and overflow tube, of a retainer divided horizontally into two compartments, and restricted means of communication between the two, each having an overflow in the form 90 of a hook, which hooks over the upper end of the overflow tube whereby the retainer is removably supported thereon.

3. The combination with a flushing-tank and overflow tube, of a retainer divided 95 horizontally into two compartments, and restricted means of communication between the two, each having an overflow in the form of a hook, which hooks over the upper end of the overflow tube whereby the retainer is removably supported thereon, a re- 100 fill pipe discharging into the retainer, and a clamp which assists in holding the retainer on the overflow tube.

4. A retainer for flushing-tanks divided 105 horizontally into two compartments, each having an outlet, a threaded opening in the partition between the two compartments,

and a screw-cap having a hole formed therein whereby communication is formed between the two compartments of the retainer, said screw-cap removably secured in the threaded opening in the partition between the two compartments.

5. A retainer for flushing-tanks divided horizontally into two compartments, each having an outlet, a threaded opening in the 10 partition between the two compartments, a screw-cap having a hole formed therein

whereby communication is formed between the two compartments of the retainer, and a cross-bar on the screw-cap to retard the flow of liquid through the opening in the screw-cap.

In testimony whereof I affix my signature, in the presence of two witnesses.

WILLIAM V. ANDREWS.
